UNITED STATES PATENT OFFICE.

HENRY B. BEACH AND HENRY KAYSER, OF MERIDEN, CONNECTICUT,
ASSIGNORS TO THE INTERNATIONAL SILVER COMPANY, OF MERI-
DEN, CONNECTICUT, A CORPORATION OF NEW JERSEY.

DESIGN FOR A SUPPORTING BASE OR STANDARD FOR CANDELABRA.

No. 37,780.

Specification for Design.

Patented Jan. 9, 1906.

Application filed December 5, 1905. Serial No. 290,489. Term of patent 7 years.

To all whom it may concern:

Be it known that we, HENRY B. BEACH and HENRY KAYSER, citizens of the United States, residing at Meriden, in the county of New Haven and State of Connecticut, have jointly invented a new, original, and ornamental Design for a Supporting Base or Standard for Candelabra, of which the following is a specification, reference being had to the accompanying drawings, forming part hereof.

Figure 1 is a front elevation, and Fig. 2 is a sectional plan view.

We claim—

The ornamental design for a supporting base or standard for candelabrum, as shown.

HENRY B. BEACH.

HENRY KAYSER.
